UNITED STATES PATENT OFFICE.

THOMAS BILYEU, OF PORTLAND, OREGON.

COIN-DELIVERING MACHINE.

1,114,574.

Specification of Letters Patent.

Patented Oct. 20, 1914.

Application filed September 24, 1909, Serial No. 519,489. Renewed January 30, 1912. Serial No. 674,378.

To all whom it may concern:

Be it known that I, THOMAS BILYEU, a citizen of the United States, residing at Portland, in the county of Multnomah and State of Oregon, have invented certain new and useful Improvements in Coin-Delivering Machines, of which the following is a specification.

A machine for selecting and delivering money in predetermined amounts in accordance herewith comprises primarily a plurality of holders for coins of different denominations, ejector mechanism composed of members arranged to eject or deliver selected coins from the holders under the control of suitable manipulative means such as keys. An actuator is adapted to operate the ejector means after certain selector devices have been set by the manipulative means to render associated ejectors operative, and an especially advantageous feature of the invention, resides in the peculiar coöperation of the above instrumentalities, whereby the load on the actuator is reduced to a minimum because the ejectors are normally disconnected therefrom, and therefore not necessary to be moved except when selected for operation.

An object of the invention has been to provide a special arrangement of selectors having cam means coöperating with swinging bars of the manipulative devices, so that the movement of the latter may be imparted to the selectors easily and positively.

Still another object of the invention has been to provide coöperating instrumentalities as hereinbefore described including the selectors which are adapted to move the ejector bars bodily in one direction into operative relation to the actuator aforesaid, and means preferably movable in opposite direction and positively operated by the actuator to render selected ejector bars inoperative again when the coin delivery operation has been effected.

In the drawings, Figure 1 is a plan view of the machine, certain parts being broken away; Fig. 2 is a partial rear elevation and partly in section; Fig. 3 is a transverse vertical section substantially on the line A—A of Fig. 1; Fig. 4 is a fragmentary detail and plan view of certain parts hereinafter described; Fig. 5 is an elevation of the parts indicated in Fig. 4; Fig. 6 is an end view

of a part of the mechanism of Fig. 4; Fig. 7 is a detail plan view of one of the keys and the parts connected for operation therefrom; Fig. 8 is a view in elevation of the same parts shown in Fig. 7, and Fig. 9 is a diagram showing one form or arrangement of operating bars for all of the coin tubes.

Throughout the following description and on the several figures of the drawings, similar parts are referred to by like reference characters.

As indicated in Fig. 1, the machine includes a series of tubes open at their tops for the reception of coins of different denominations, herein indicated as fourteen in number, although it is to be understood that the exact number of tubes and the corresponding capacity of the machine may be varied if desired without departing from the principle involved in its operation. The device includes four sets of keys, the sets being represented by the letters *a*, *b*, *c*, and *d*, and each set having nine keys numbered consecutively from 1-9. As viewed in Fig. 1, the keys *a* represent dollars in multiples of ten, from \$10 to \$90; set *b* represent dollars in units, from 1-9; set of keys *c* represent dimes from 1-9, and set *d* represent cents from 1-9.

The arrangement of coin tubes shown includes as many groups as there are sets of keys. The first group of tubes are indicated by the letters A, B and C, said group pertaining to the set of keys *a*. The second group of tubes are indicated by the letters D, E and F and pertain to the set of keys *b*. The third group of tubes are indicated by the letters G, H, I, J and K and pertain to keys of set *c*. The fourth group of tubes, indicated by the letters L, M and N, pertain to the set of keys *d*. Tube A is to be supplied with twenty-dollar gold pieces or double eagles, which are to be delivered therefrom either singly or in twos at the will of the operator. Tube B is to be supplied with double eagles, which are to be delivered therefrom always by twos. Tube C is to be supplied with ten-dollar gold pieces or eagles, which are always to be delivered therefrom singly. Tube D is to be supplied with five-dollar gold pieces, which are to be delivered therefrom singly. Tube E is to be supplied with silver dollars, which are to be delivered therefrom either

singly or by twos. Tube F is to be supplied with silver dollars, and is intended to deliver the same by twos only. Tube G is to be supplied with half dollars which are to be delivered singly. Tube H is to be supplied with quarters, which are to be delivered singly. Tubes I and J are each to be supplied with dimes, which are to be delivered therefrom singly in each case, it being found in practice that since dimes become worn so much by usage, it is impossible to rely upon the delivery of either one or two from the same tube, as is the case with larger coins. Tubes K and L are each supplied with nickels, from each of which the coins are to be delivered singly. Tube M is supplied with pennies, which are to be delivered therefrom either singly or in twos, and tube N is supplied with pennies, to be delivered in twos only.

Upon depression of key 1 of set *a* the ejector mechanism of tube C will be set to deliver an eagle therefrom. Upon depression of key 2 of the same set the ejector mechanism of tube A will be set to deliver a double eagle from tube A. The depression of key 3 will set the mechanisms of both of tubes A and C so as to deliver \$30. The depression of key 4 will set the mechanism of tube B so as to deliver two double eagles. The depression key 5 will set the ejector mechanisms of both of tubes B and C. The depression of key 6 will set the ejector mechanism of tube A to deliver one double eagle and that of tube B so as to deliver simultaneously \$60. The depression of key 7 will add the setting of the mechanism of tube C to that just described. The depression of key 8 will adjust the delivery mechanism of tubes A and B so as to deliver two double eagles from each, and the depression of key 9 will adjust all of the ejector mechanisms of this group so as to deliver \$90. The foregoing illustration of the function or purpose of the first group of tubes and the associated set of keys is illustrative of the manner in which the other portions of any amount of change desired may be obtained. Referring to the second group of tubes and the set of keys *b*, and following the same reasoning as indicated above in connection with the first group it will be appreciated that to depress key 1 of set *b* a silver dollar will be prepared to be delivered from tube E; the depression of key 2 would set the mechanism of tube F to deliver \$2; the depression of key 3 would set the mechanisms of tubes E and F to deliver \$3, and the depression of key 4 would set the same mechanism to deliver \$4. The depression of key 5 would set the mechanism of tube D to deliver a five-dollar gold piece, and so on throughout this group. From the foregoing it is believed that the function or purpose of all

the groups in making the various amounts of change will be understood without further detailed suggestion.

Referring now to the specific construction of the present machine, 1 denotes a suitable casing or frame and 2 are holders or tubes hereinbefore referred to, and from the bottom portions of which the coins are adapted to be delivered.

Mounted in the rear portion of the machine and lengthwise thereof is an actuator comprising a rock shaft 3 and a plurality of arms or rockers 4 mounted thereon for movement therewith. At their upper ends the arms 4 are adapted to coöperate with the ejector mechanism which comprises a plurality of groups of devices arranged to coöperate with the various corresponding groups of coin holders 2, each ejector device including a rack 6, constituting an actuating member, and having teeth at its rear end in mesh with teeth at the upper end of an adjacent arm 4. The front end of the rack 6 carries a pivoted gravity catch 7 supported at 8 and adapted to engage with an opening 7a in the ejector bar 9.

The bar 9 is pivotally connected at its front end, as shown at 10 to an ejector slide 11 and said bar 9 is movable in a horizontal plane, or the same plane as its ejecting movement so as to be adjusted in a position in which it is in substantial alinement with the parts 6 and 11, whereupon it is operative by the actuator to effect delivery of a coin or coins from the tube or holder 2 therefor. Normally, however, the various ejector bars 9 are so arranged that their rear ends are not in the paths of movement of the racks 6, suitable selector means being provided for operating one or more of the ejector bars 9 to move the same into a position in alinement with corresponding racks 6 so that when thus operatively disposed, the coins 12 may be delivered when the actuator is operated.

The selector mechanism comprises a plurality of selectors 20 consisting of sets of bars arranged longitudinally of the machine, in sets that correspond with the groups of ejectors and formed with projections 21 extending upwardly therefrom so as to engage the ejector bars 9 when the selectors are operated. The selectors are supported in guides 22 and are operable by manipulative means consisting of sets of bars 15 and 16 pivotally mounted at opposite ends on longitudinal pivot rods 17 and 18 respectively. Keys 19 which form the rows *a*, *b*, *c* and *d*, the operation of which has been before described, are secured at their lower ends to lateral extensions on the free ends of the bars 15 and 16 and each key has a suitable finger piece at its upper extremity. Each bar of the various sets 15 and 16 coöperates with one or

more of the selectors 20, being adapted to engage with a cam 23 on an adjacent end of a co-operating selector, whereby on depression of the key and the bar with which it is connected, the latter will engage the cam 23 of one or more selectors and impart to the latter longitudinal movement, causing co-operation of the selectors with the ejector bars 9 to thus move the latter into alignment with the racks 6 ready for operation by the actuator. The number of projections or lugs 21 carried by each selector 20 will depend upon the number of ejector bars which it is designed that said selector shall operate, and this matter is governed by the denominations of coins which a predetermined selector will select.

The preferable arrangement of parts contemplates that there shall be as many selector bars as there are keys 19 and a set of selector bars will comprise those adjacent to one another and operable by a single row of the keys of the entire bank provided.

The operation of the device briefly is as follows: When it is desired to make any particular amount of change, such for example as \$47.53, the operator standing in front of the machine as indicated in Fig. 1, will depress key 4 of set *a*, indicating the number of eagles or tens of dollars desired, key 7 of set *b*, indicating the number of units of dollars desired, key 5 of set *c*, indicating the number of dimes, and key 3 of set *d*, indicating the number of cents. When said keys are depressed the ejector mechanisms will be brought into operative position with reference to tubes B, D, F, G, M and N, all of the other movable members 9 of the ejector mechanisms remaining in their normal inoperative position. The operator will then draw upon the lever 29 connected to the rock shaft 3, causing the racks 6, with which the aforesaid ejector mechanisms have been brought into alignment, to move toward the tubes and thereby deliver the desired coins from the tubes indicated, all of which would be performed simultaneously by a single sweep or operation of the lever 29. In order to restore the ejectors to their normal position, the gravity catches 7 are so arranged as to engage in holes 7^a on the free ends of the links 9 at the time the ejectors are operated to discharge or deliver the coins. Each of the catches will therefore remain in engagement with the respective ejector bar 9 while the coins are being delivered, and upon the reverse movement of the lever 29 and rock shaft 3, the racks 6 to which the catches 7 are pivoted will drag or draw the members 9 and 11 rearwardly until the rear end of each of the catches is brought into engagement with the lower surface of a release rod 8^a, which extends parallel to the rock shaft 3 and substantially throughout the length of the machine. Such engagement of the pawls

with the rod 8^a necessitates the points or noses thereof to be withdrawn from the links 9. Slightly further movement or rotation of the rock shaft will cause a finger 27 extending upwardly therefrom to engage the rear end of a lever 24 pivoted on a vertical pivot 25, and by virtue of a connection between the front end of said lever 24 and a horizontal bar 28 all of said ejector bars will be thrown out of alignment with the respective racks 6 ready for the next change making operation, the selectors 20 and keys coacting therewith being at the same time restored. The bar 28 is connected to the lever 24 through a pin and slot connection 26. The bar 28 has lugs upon its under side for engagement with the respective ejector bars 9, to render the latter inoperative.

From the foregoing, it will be understood that the selectors 20 when operated by the manipulative means comprising the keys 19, will effect movement of the ejector bars bodily in the plane of their ejecting movement, and in one direction, while the bar 28 is operable by movement in the opposite direction to restore all previously selected ejectors 9 to their original position.

Having thus described the invention, what is claimed as new is:

1. In a coin delivery machine, the combination of a series of coin holders, ejector mechanism for each coin holder comprising a longitudinally movable ejector slide, an ejector bar pivotally connected at one end to said slide and having its other end normally out of alignment with the slide, a slidable actuating member spaced from but in alignment with the slide, key operated devices for bringing the selected ejector bars into alignment with the actuating members and associated slides, and means for simultaneously operating all of the actuating members and thereby moving said selected ejector mechanisms.

2. In a coin delivery machine, the combination of a series of coin holders, an ejector mechanism controlling the delivery of coins from the bottom portions of said holders, each ejector mechanism including a longitudinally movable slide, an ejector bar pivoted at one end to said slide, a rack spaced from but in alignment with the slide, an actuator arm having teeth meshing with those of the rack, key operated selectors for setting the ejector mechanism for operation by moving selected ejector bars into alignment with the racks and slide, and an actuator common to all of said slides to actuate the latter and impart corresponding movement to the ejector means.

3. In a coin delivery machine, the combination of a series of coin receptacles, delivery mechanism for each receptacle comprising an ejector slide, an ejector bar connected to said slide and movable into and out of an

- operative position, key operated selectors for moving the ejector bars into operative position, means for positively operating said ejector bars and slides in both directions, means to lock the ejector bars in operative position with respect to said slides while moving in one direction, and means to release said locking means when moving in the other direction.
10. 4. Ejector mechanism for coin delivery machines including a slide, an ejector bar connected at one end to said slide and having its other end normally out of alinement therewith, an actuator comprising a member spaced from and in alinement with the slide and with which the ejector bar is adapted to be brought into alinement, and means mounted upon said actuating member to lock said ejector bar when brought into alinement with the slide and actuating member.
15. 5. Ejector mechanism for coin delivery machines comprising an ejector slide, an ejector bar connected thereto at one end and normally free at its other end and out of alinement with said slide, an actuating member spaced from and in alinement with said slide and with which said ejector bar is adapted to be brought into alinement, and a catch pivoted upon the actuating member and arranged to interlock with the normally free end of the ejector bar when said bar is brought into alinement with the slide and actuating member for delivery operation.
20. 6. In combination, money holders, ejector mechanism therefor comprising ejector bars movable in paths intersecting the bases of the holders, an actuator common to all of said bars, selectors for rendering one or more of the ejector bars operative by the actuator, and automatically operating devices for interlocking the actuator and ejector bars on operation of said actuator.
25. 7. In a money handling machine, the combination of a plurality of coin receptacles arranged in groups adapted to contain different denominations of coins, a casing on which said receptacles are supported, ejectors for said receptacles selector mechanism associated with the coin receptacles and juxtaposed in relation thereto for controlling the operation of the ejectors aforesaid, said selector mechanism comprising devices grouped to correspond with the grouping of the receptacles aforesaid and being movable transverse to the line of movement of the ejectors in order to render one or more of the latter operative for the discharge of coins, a keyboard located at a side of the receptacles and composed of rows of keys, each row controlling the discharge of coins from a certain group of receptacles, mechanism beneath said keyboard and including members intermediate the keys and the selector devices aforesaid, whereby by depression of the keys, movement of certain selector devices will be controlled to thereby control in turn the action of coöperating ejectors, and an actuator common to the ejectors for operation thereof as determined by the key controlled selector mechanism.
30. 8. In a money handling machine, the combination of ejectors arranged in parallel relation and movable longitudinally, a plurality of parallel selectors also movable longitudinally but in a direction transverse in respect to the ejectors, means intermediate the selectors and ejectors whereby the said transverse movement of the selectors is communicated to the ejectors, and manipulative means to operate the selectors and ejectors.
35. 9. In a money handling machine, the combination of ejectors arranged in parallel relation and movable longitudinally, a plurality of parallel selectors also movable longitudinally but in a direction transverse in respect to the ejectors, means intermediate the selectors and ejectors whereby the said transverse movement of the selectors is communicated to the ejectors, manipulative means movable rectilinearly in respect to the selectors to operate the latter, and means for actuating the ejectors after the selection of the same.
40. 10. In combination, money holders, ejector mechanism therefor comprising a plurality of ejector bars coöperating with said holders, an actuator consisting of a plurality of actuating arms normally out of alinement with respect to said ejector bars, selector mechanism for throwing one or more of the ejector bars into alinement with the actuating arms so as to be operated thereby, and means for moving said actuating arms and simultaneously interlocking selected ejector bars with their coöperating actuating arms.
45. 11. In combination, money holders, ejector mechanism therefor comprising a plurality of ejector bars coöperating with said holders, an actuator consisting of a plurality of actuating arms normally out of alinement with respect to said ejector bars, a selector mechanism for throwing one or more of the ejector bars into alinement with the actuating member so as to be operated thereby, means for moving said actuating members and simultaneously interlocking selected ejector bars with their coöperating actuating members, and means for releasing the selected ejector bars from the actuating members thereof on return movement of the latter.
50. 12. In combination, money holders, ejector means therefor comprising ejector bars, an actuator common to all of said ejector bars but normally inoperative in relation thereto, and selector mechanism for effecting bodily movement of selected ejector bars into positions in which they are operable by said actuator comprising selector bars slid-

able transversely to the ejector bars and having means to actuate the latter.

13. In combination, money holders, ejector means therefor comprising ejector bars, an actuator common to all of said ejector bars but normally inoperative in relation thereto, selector mechanism for moving selected ejector bars in one direction into positions in which they are operable by said actuator on initial movement of the latter, and means operable by the actuator on subsequent movement thereof, for positively engaging and shifting the ejector bars into positions inoperative with respect to the actuator.

14. In combination, money holders, ejector means associated therewith and comprising ejector bars, an actuator common to said bars, selector mechanism comprising a plurality of devices for selecting the ejector bars and moving the latter into positions in which they are operative in respect to the actuator, and means for restoring the ejector bars to their original positions comprising a single member arranged to engage all of the ejector bars.

15. In combination, coin holders, ejector bars therefor movable laterally in the plane of their ejecting movement, an actuator for causing ejecting movement of said bars, and means for shifting the ejector bars in the plane of their ejecting movement to render said bars operative or inoperative with respect to the actuator.

16. In combination, coin holders, ejector bars associated with said holders, an actuator comprising actuating arms for coöperation with the bars and movable normally without actuating the latter, selector mechanism consisting of separate selectors for shifting associated ejector bars into positions in the path of movement of the actuator arms, means comprising a single member adapted to engage all of the ejector bars to restore the latter to their normal positions, and means connecting the last mentioned member with the actuator.

17. In combination, coin holders, ejector bars associated with said holders, an actuator comprising actuating arms for coöperation with the bars and movable normally without actuating the latter, selector mechanism consisting of separate selectors for shifting associated ejector bars into positions in the path of movement of the actuator arms, means comprising a single member adapted to engage all of the actuating bars to restore the latter to their normal positions, a lever connected to the last mentioned member, and means carried by the actuator for shifting said lever.

18. In combination, money holders, ejector means therefor consisting of a plurality of ejector bars, an actuator for said bars and normally disconnected therefrom, means for

shifting one or more of the ejector bars into the path of movement of said actuator, and means for interlocking the shifted ejector bars and actuator on initial movement of the latter.

19. In combination, money holders, ejector means therefor consisting of a plurality of ejector bars, an actuator for said bars and normally disconnected therefrom, means for shifting one or more of the ejector bars into the path of movement of said actuator, means for interlocking the shifted ejector bars and actuator on initial movement of the latter, and means for simultaneously releasing the interlocked ejector bars from the actuator during subsequent movement of the latter.

20. In combination, money holders, ejector means therefor consisting of a plurality of ejector bars, an actuator for said bars and normally disconnected therefrom, means for shifting one or more of the ejector bars into the path of movement of said actuator, means for interlocking the shifted ejector bars and actuator, means for simultaneously releasing the ejector bars from the actuator during subsequent movement of the latter, and means for shifting the released ejector bars back to their normal positions during said subsequent movement of the actuator.

21. In combination, money holders, ejector means therefor consisting of a plurality of ejector bars, an actuator for said bars and normally disconnected therefrom, means for shifting one or more of the ejector bars into the path of movement of said actuator, means for interlocking the shifted ejector bars and actuator on initial movement of the latter, means for simultaneously releasing the ejector bars from the actuator during subsequent movement of the latter, and means for shifting the released ejector bars back to their normal positions during said subsequent movement of the actuator, the last mentioned means comprising a lever operable by the actuator and a bar adapted to engage all of the ejector bars.

22. An ejector device for coin delivery machines consisting of an ejector bar, an actuating arm normally spaced from said bar and inoperative in respect thereto, means for moving the bar into a position in which it is operable by the arm, and a catch operable by the arm to interlockingly connect the latter with the bar when the arm is actuated.

23. An ejector device for coin delivery machines consisting of an ejector bar, an actuating arm normally spaced from said bar and inoperative in respect thereto, means for moving the bar into a position in which it is operable by the arm, a catch operable by the arm to interlockingly connect the latter with the bar when the arm is actuated, and a member arranged to engage and tilt said

8
catch to release the arm from the ejector bar.

24. An ejector device for coin delivery machines consisting of an ejector bar, an actuating arm normally spaced from said bar and inoperative in respect thereto, means for moving the bar into a position in which it is operable by the arm, a catch operable by the arm to interlockingly connect the latter with the bar when the arm is actuated, a member arranged to engage and tilt said catch to release the arm from the ejector bar, and a member arranged to shift the ejector bar after the same has been released from the arm.

25. In combination, money holders, ejector mechanism therefor, selector means comprising a plurality of longitudinally sliding selectors having cams on corresponding ends, manipulative means comprising keys, and bars operable by the keys and arranged to swing transversely of the selectors and engaging the cams for imparting movement to the selectors.

26. In a money handling machine, the combination of money receptacles, ejector bars coöperating therewith, and longitudinally slid able selector bars movable transversely to the ejector bars and in operative connection therewith.

27. In a money handling machine, the combination of money receptacles, ejector bars coöperating therewith, parallel longitudinally movable selector bars arranged transverse to the ejecting movement of the ejector bars and having members in direct engagement therewith, and manipulative means to operate the selectors.

28. In a money handling machine, the combination of money receptacles, longitudinally movable ejector bars coöperating therewith, selectors engaging the ejector bars, actuating means for imparting longitudinal movement to the ejectors, and means for operating the selector bars to cause lateral movement of the ejector bars in the plane of their longitudinal movement.

29. In a money handling machine, coin holders, ejector bars operating in paths intersecting the bases of the holders, an actuator, selector mechanism for setting the bars in a predetermined position in relation to the actuator, and a single bar operable reverse to the selector mechanism to restore selected ejector bars to their normal positions.

30. In a money handling machine, coin holders, ejector bars operating in paths intersecting the bases of the holders, an actuator, selector mechanism for setting the bars in a predetermined position in relation to the actuator, and a single bar having means engaging all of the ejector bars and operable reverse to the selector mechanism to restore selected ejector bars to their normal positions.

31. In a money handling machine, the combination of a plurality of coin receptacles arranged in groups adapted to contain different denominations of coins, ejectors for said receptacles a casing on which 70 said receptacles are supported, selector mechanism associated with the coin receptacles and juxtaposed in relation thereto for controlling the operation of the ejectors aforesaid, said selector mechanism comprising devices grouped to correspond with the grouping of the receptacles aforesaid and being movable transverse to the line of movement of the ejectors in order to render one or more of the latter operative for the 80 discharge of coins, a keyboard located at a side of the receptacles and composed of rows of keys, each row controlling the discharge of coins from a certain group of receptacles, mechanism beneath said keyboard and including members intermediate the keys and the selector devices aforesaid, whereby by depression of the keys, movement of certain selector devices will be controlled to thereby control in turn the action of coöperating 90 ejectors, an actuator comprising a handle, a shaft with which said handle is connected, and means intermediate said shaft and the ejectors for effecting money discharge movement of the ejectors, the selector devices being adapted to be normalized by the operation of the handle at a predetermined point in the return movement of the latter.

32. In a money handling machine, the combination of money holders, ejector means therefor, selector bars, and means for operating the latter comprising keys in alinement, and reversely arranged sets of swinging bars, one set of said bars having lateral extensions coacting with some of the 105 keys and the other set having opposite lateral extensions coacting with the remainder of the keys.

33. In combination, money holding means, ejectors coacting therewith, actuating members for the ejectors, means for rendering the ejectors operative relative to the actuating members, and means for interlocking the operative ejectors and actuating members on operation of the latter.

34. In combination, money holding means, ejectors coacting therewith, actuating members for the ejectors, means for rendering the ejectors operative relative to the actuating members, means for interlocking the operative ejectors and actuating members on operation of the latter in one direction, and means for releasing and restoring the operative ejectors to their normal positions 120 during movement of the actuating members in an opposite direction.

35. In a coin handling machine, coin holders disposed in groups, ejector means including a plurality of ejectors located in 130 rear of the groups separate from those in

other groups, said selecting means being disposed in rear of the coin holders, a keyboard adjacent to one end of the grouped coin holders and comprising manipulative devices for controlling the action of the selecting means, and a main actuator for the ejectors to cause money discharging operation thereof and arranged at an end of the machine at one side of the keyboard.

36. In a money handling machine, the combination of money holders, ejector mechanism therefor including ejectors to discharge money from said holders, means for controlling the discharging action of the ejectors comprising selectors operable to render predetermined ejectors operative, a main actuator for the ejectors, means to lock the selected ejectors to the actuator on movement of the latter, and means to release the ejectors from the actuator.

37. In a money handling machine, the combination of money holders, ejector mechanism therefor including ejectors to discharge money from said holders, means for controlling the discharging action of the ejectors comprising selectors operable to render predetermined ejectors operative, a main actuator for the ejectors, an automatically operating catch to connect a selected ejector with the actuator on operation of the latter, and means to render the catch inoperative at a predetermined point in the movement of the actuator.

38. In a money handling machine, the combination of money holders, ejector mechanism therefor including ejectors to discharge money from said holders, means for controlling the discharging action of the ejectors comprising selectors operable to render predetermined ejectors operative, a main actuator for the ejectors, an automatically operating catch to connect a selected ejector with the actuator on operation of the latter in one direction, and means to automatically operate the catch to release the said ejector from the actuator during movement of the latter in an opposite direction.

39. In a money handling machine, the combination of money holders, ejector mechanism therefor including ejectors to discharge money from said holders, means for controlling the discharging action of the ejectors comprising selectors operable to render predetermined ejectors operative, a main actuator for the ejectors, means other than the selectors to lock selected ejectors to the actuator on movement of the latter, and means to release the ejectors from the actuator.

40. In a money handling machine, a plurality of money holders, slideable ejectors associated therewith for engaging and discharging money from said holders, selectors coöoperating with said ejectors, manipulative devices controlling the operation of

said selectors whereby the ejectors may be rendered operative to perform their discharging function, mechanism for actuating the various ejectors including a shaft, arms movable with said shaft for coöperation with the ejectors, and a connection intermediate each arm and the associated ejector permitting movement of the ejector by the arm and movement of the arm independently of the ejector.

41. In a money handling machine, a plurality of money holders, slideable ejectors associated therewith for engaging and discharging money from said holders, selectors coöoperating with said ejectors, manipulative devices arranged in rows of nine each and each row controlling the operation of predetermined ones of said selectors whereby the ejectors may be rendered operative to perform their discharging function, mechanism for actuating the various ejectors including a shaft, arms movable with said shaft for coöperation with the ejectors, and catch means between each arm and a coacting ejector operable automatically to cause simultaneous movement of the arm and the ejector, and adapted to permit free movement of the arm without actuating the ejector.

42. In a coin delivery machine, the combination of a plurality of coin receptacles, an ejector bar associated with each of said receptacles, an actuating member for moving each ejector bar and normally inoperative with relation thereto, means for operating the actuating member, and means for moving the ejector bar bodily in the plane of its ejecting movement to cause it to assume an operative position with respect to its actuating member preliminary to its operation to deliver a coin.

43. In a coin delivery machine, the combination of a plurality of coin receptacles, sliding ejector bars associated therewith and arranged so that corresponding ends are adapted to engage coins in said receptacles, a plurality of actuating arms arranged for effecting sliding movement of the ejector bars and normally inoperative in respect thereto, selective mechanism for engagement with opposite corresponding ends of the ejector bars to cause said ends to move in the plane of their ejecting movement to assume positions wherein they are engageable by their actuating arms, and means for operating the actuating arms.

44. In a money handling machine, a plurality of money holders, slideable ejectors associated therewith for engaging and discharging money from said holders, selectors coöoperating with said ejectors, manipulative devices controlling the operation of said selectors whereby the ejectors may be rendered operative to perform their discharging function, mechanism for actuating the various

ejectors including a shaft, an arm rigid on and movable with said shaft for coöperation with an ejector, and a connection intermediate said arm and the associated ejector permitting movement of the ejector by the arm and movement of the arm independently of the ejector.

45. In a machine for delivering money in predetermined amounts, the combination of money holders adapted to receive coins of different denominations, ejector mechanism in the rear of said holders to discharge coins therefrom, selector means controlling the operation of the ejector mechanism, predetermining means governing the action of the selector, and ejector means aforesaid, and comprising groups of manipulative keys disposed at one side of the money holders in parallel relation, said keys being operable to selectively control the discharge of money from the various holders above mentioned, an actuator consisting of a handle located at the side of the keys opposite that at which the holders are disposed, and adapted to initially operate the ejectors and subsequently normalize the keys, and a chute to deliver

the money discharged from the receptacles and common to the latter.

46. In a machine for delivering money in predetermined amounts, the combination of money holders adapted to receive coins of different denominations, ejector mechanism in the rear of said holders to discharge money therefrom, selector means controlling the operation of the ejector mechanism, predetermining means governing the action of the selector and ejector means aforesaid, and comprising groups of manipulative keys disposed at one side of the money holders in parallel relation, said keys being operable to selectively control the discharge of money from the various holders above mentioned, an actuator, and means whereby the actuator may initially operate the ejectors and subsequently restore the selector means and keys to normal positions, and a chute to receive and deliver money from the holders above mentioned.
